OVEN DOOR HINGE

Filed May 6, 1929

Inventor:—
William D. Antrim,
By his Attorneys
Howard & Howard

UNITED STATES PATENT OFFICE

WILLIAM D. ANTRIM, OF GLOUCESTER, NEW JERSEY, ASSIGNOR TO ROBERTS & MANDER STOVE COMPANY, OF PHILADELPHIA, PENNSYLVANIA, A CORPORATION OF PENNSYLVANIA

OVEN-DOOR HINGE

Application filed May 6, 1929. Serial No. 360,976.

My invention relates to certain improvements in the spring hinges for the oven doors of ranges as disclosed in the patent granted to C. V. Roberts and K. C. Farnsworth on the 5 11th day of November, 1924, No. 1,515,413.

The object of the present invention is to provide means for readily securing the springs in position, and to provide a cover plate and casing which enclose the movable 10 parts of the door hinge.

In the accompanying drawing:

Fig. 1 is a rear view of a portion of the front frame of a range, with the door in the closed position;

15 Fig. 2 is a sectional plan view on the line 2—2, Fig. 1;

Fig. 3 is a sectional elevation on the line 3—3, Fig. 1; and

Fig. 4 is a sectional perspective view showing a portion of the door and frame, with a spring in position.

The oven door frame 1 and the door are constructed substantially as shown in the patent noted above. At the rear of the frame 25 is a box 2 which encloses the spring hinge mechanism. The door 3 fits the opening in the frame 1. On the door are two rearwardly extending arms 4 which carry the hinge pintles 5. The arms are shaped as shown in Fig. 30 3, to allow the door to freely open and close and conceal the hinge when in the closed position.

On each hinge pintle is a coiled spring 6. One end of each spring is attached to its 35 pintle, while the other end 7 extends through a bayonet slot 8 in the outer wall 9 of an enclosing box 2. The outer end of the spring is formed into an eye to provide a hand-hold, by grasping which the end of the spring can 40 be readily inserted in the bayonet slot or removed therefrom.

On the inside of the oven frame is an enclosing casing 11 which is secured by screw-bolts 12 to slotted lugs on the enclosing box 2. 45 This casing covers and protects the end of the springs that extend through the bayonet slots.

In the present construction the box is open at the top, and is closed by a separate cover plate 13 which extends from one hinge to the 50 other as shown in Fig. 1, and is secured to an

inwardly projecting flange 14 on the box by bolts 15, the flange being slotted to receive the bolts.

Lugs 16 on the box hold the hinge elements in a central position when the door is in the open position. A projection 17 on each pintle extends past its lug as shown, and is notched to receive one of the springs which must be secured to the pintle.

While my invention has been described as a door hinge of a gas range, it will be understood that it can be used also as a hinge of an oven door for a gas or electric range, or in fact any place where it is desired to conceal the hinge, and to provide for closing the door when in partially open position or allowing the door to remain open when in the open position.

I claim:

1. The combination in a frame, of a door having rearwardly extending projections; pintles on said extensions; a coiled spring on each pintle, one end of the spring being secured to the pintle; a box enclosing the hinge mechanism, the rear wall of the box having a bayonet slot therein, and the free end of the spring extending through the slot, the slot allowing the spring to be retained in position or readily removed from the slot when it is desired to detach the door from the frame.

2. The combination in a door frame, of a door having rearwardly extending projections; horizontal pintles on each projection; a coiled spring on each pintle, the spring being secured to the pintle; a box enclosing the spring mechanism, the rear wall of the box having bayonet slots therein through which the free end of each spring extends; and an enclosing casing for the box and the ends of the spring, said casing being secured to the box.

3. The combination in a door frame, of a door having rearwardly extending projections; horizontal pintles on each projection; a coiled spring on each pintle, the spring being secured to the pintle; a box enclosing the spring mechanism, the rear wall of the box having bayonet slots therein through which the free end of the spring extends; an

enclosing casing for the box and the ends of the spring, said casing being secured to the box; and a detachable cap plate secured to the box, said cap plate being located between 5 the two rearwardly projecting hinge portions on the door.

WILLIAM D. ANTRIM.
